UNITED STATES PATENT OFFICE.

EMIL BENTE AND PAUL STUHLMANN, OF BARMEN, GERMANY, ASSIGNORS TO MAX HENKELS, OF NEW YORK, N. Y.

LACE WITH STELLATED MESHES.

Application filed December 27, 1922. Serial No. 609,270.

To all whom it may concern:

Be it known that we, EMIL BENTE and PAUL STUHLMANN, citizens of the German Empire, residing at Barmen, Germany, have 5 invented certain new and useful Improvements in Laces with Stellated Meshes, of which the following is a specification.

This invention relates to the production of lace with rhombic ground work. The 10 object of the invention is to produce a lace of said character in a more simple, rapid and economical way, viz from a very small number of threads, and to obtain a pleasant looking and firmly braided lace which retains 15 its design and will resist distortion. With this and other objects in view our invention consists in a novel way of arranging, interbraiding and interconnecting the threads to form the lace as is fully set forth 20 in the following description with reference to the annexed drawing which shows, by way of example, three embodiments of our invention.

On the drawing:

25 Fig. 1 is a piece of the new lace in natural size,

Fig. 2 is a part of that lace drawn on an enlarged scale,

30 Fig. 3 is a piece of an alternative form of our lace in natural size, and

Fig. 4 is a piece of another alternative form of the new lace, also in natural size.

Referring now to Fig. 1, the ground-work 35 of the lace shown seems to be composed of numerous six-jagged stars connected with each other at their contiguous points.

This peculiar lace-net is, according to our invention, produced by forming several spaced rows of rhomb-like meshes a , a arranged in staggered relation to each other, and by connecting each four adjacent meshes, at their corners facing one another, by means of transversally arranged staves or spokes C, D, as more clearly shown in Fig. 2.

45 The edges of the rhomb-like meshes a , a consist of strips or pillars comprising each two entwisted threads, and what is more, the edges of those meshes a , a which belong to the same row are commonly formed by 50 means of a pair of strips, 1 and 2, 3 and 4, 5 and 6 etc. which extend over the entire length of the fabric. There is a great number of strips arranged in pairs side by side depending on the width of the lace to be 55 produced, spaces of equal width being left

between each adjacent pair of strips. At certain intervals, for instance at the places A, A¹, B, B¹, B², (see Fig. 2) those strips 1 and 2, 3 and 4, 5 and 6 etc., which belong to the same pair are connected with each other by braiding together all four threads of both strips, the connecting places of each pair of strips being thereby arranged in staggered relation to the connecting places of the adjoining pairs of strips. 60

At the connecting places A, A¹, B, B¹ and so on above explained two threads each of the four interbraided threads, for instance the threads a^2 , a^4 , are in opposite directions, temporarily conducted out of the braids 65 formed at said places, and subsequently led back into the braids so as to produce two transversal or weft-like staves or spokes C, D having each the shape of a loop. While forming said loop like spokes or bars the threads a^2 , a^4 are, each at another side of the respective braid, for instance of the braid A, connected with those strips of the two adjacent 70 pairs of strips which immediately adjoin to that pair of strips from which the respective loops are taken, for example with the strips 2 and 5, the said connections being effected by interlacing or interbraiding the threads a^2 , a^4 with the threads of the said strips 2 and 5. As the braided portions A, A¹ and 75 B, B¹ in each adjacent pair of strips are arranged in staggered relation, the connections of the free ends of the loops C, D with adjacent strips lie exactly in the middle between each two braids, B, B¹ for example. 80

In consequence of their being connected by means of the loops, C, D to the adjacent pairs of strips, the two strips belonging to the same pair of strips are between each two braided portions A and A¹, B and B¹, B¹ and B² respectively, spread apart, and thereby drawn each into a zig-zag line. 85 Thus the rows of rhomb-like meshes a , a are formed which latter, in consequence of their being arranged in staggered relation, 90 lie each in face of the space between two succeeding meshes of the adjacent row. Simultaneously, the rhomb-like meshes a , a are, at their corners facing each other, tightly connected with another by said 95 spokes C, D. Finally the space between each two rows of meshes a , a is, also by means of the loop-like spokes C, D, divided into meshes of a similar rhomb-like shape. Thus the latter form in combination with 100 105 110

the meshes *a*, *a* the six-jagged stars which give the lace-net its peculiar character.

The threads *a'*, *a'* which, during the formation of the loops *C*, *D*, remain in the 5 braided portions *A*, *A'*, *B*, *B'* and so on, are preferably conducted, without crossing one another, straight through in the longitudinal direction of the fabric, so that in the middle of each of said braids holes or eyes 10 *b*, *b* are formed.

The edges of the lace, may, as shown in Figs. 1 and 2, be formed in a known manner by single strips *o*, *o* running straight through in the longitudinal direction of the fabric. 15 Said strips are alternately connected to the outwardly directed corners of the meshes *a*, *a* of the marginal rows of meshes and to the loops *C*, *D* extending outwardly from the connecting places *B*, *B'* of said marginal 20 meshes.

As is evident from an inspection of Figs. 1 and 2, by the novel arrangement of threads according to our invention a very pleasant and particularly clear lace-net with 25 stellated meshes is produced. Furthermore, the number of threads in a given width of the lace is a comparatively small one so that our new lace can not only be manufactured on small machines, but, in consequence 30 of the comparatively small quantity of thread-material required for a given length, is rather cheap.

Instead of connecting the rows of meshes *a*, *a* by means of the loops described, these 35 connections may, if desired, also be effected by interchanging one thread each between the immediately adjoining strips of two adjacent pairs of strips so as to form also transverse or weft-like staves or spokes.

40 In the alternative form of lace shown in Fig. 3 a net with stellated meshes is formed substantially in the same manner as above explained with reference to Figs. 1 and 2. The difference consists only in that the lateral 45 corners of the meshes *a*, *a* belonging to adjacent rows are connected with each other by means of intermediate strips *c*, *c* running straight through in the longitudinal direction of the fabric and extending over 50 the entire length of the latter. By these means a distortion of the lace-net in its longitudinal direction is entirely avoided. In the form of lace, shown in Fig. 3, of course, the adjacent rows of meshes *a*, *a* are to be 55 spaced in such a manner that the lateral corners of the meshes belonging to the ad-

jacent rows lie on a straight longitudinal line.

To the lace-net described any desired patterns producible on the single-thread lace-braiding machine, as tufts, spiders, leaflets or the like may be applied. In the lace shown in Fig. 4 there are, for example, spiders *d*, *d* worked in by interlacing the threads of a plurality of adjoining strips in 60 a weave-like manner. Furthermore the lace illustrated in Fig. 4 is provided with borders *f*, *f* of the type usually produced on the single-thread lace-braiding machine.

We wish to state that our invention is not 70 restricted to the exact forms of lace shown and described; for many alterations and variations may suggest themselves to those skilled in the art, without departing from 75 the spirit of our invention as pointed out in the claims.

Claims:

1. The method of producing lace with rhombic ground work which consists in forming pairs of warp-pillars, each pillar 80 consisting of but two threads, twisted together to form the pillar, and in interconnecting said pairs of pillars with each other and with the adjacent pillars so as to form spaced rows of rhombic shaped figures, and 85 the latter in adjacent rows being in staggered relation to each other said interconnection being accomplished by interbraiding at intervals the four threads of each pair of pillars and simultaneously forming transversely extending loop bars at the point of 90 interbraiding.

2. A lace with rhombic ground work, having pairs of warp-pillars, each pillar consisting of two threads twisted together to 95 form the pillar and each pair of pillars being connected with each other and with the adjacent pillars so as to form spaced rows of rhombic figures, the latter in adjacent rows being in staggered relation to 100 each other, said interconnection being accomplished by interbraiding at intervals the four threads of each pair of pillars and simultaneously forming transversely extending loop bars at the point of interbraiding. 105

In testimony whereof we affix our signatures in presence of two witnesses.
